UNITED STATES PATENT OFFICE.

THOMAS G. CRAIGHEAD, OF SEATTLE, WASHINGTON.

STOCKING.

1,308,483.

Specification of Letters Patent.

Patented July 1, 1919.

Application filed March 31, 1919. Serial No. 286,382.

To all whom it may concern:

Be it known that I, THOMAS G. CRAIGHEAD, a citizen of the United States, residing at Seattle, in the county of King and 5 State of Washington, have invented certain new and useful Improvements in Stockings, of which the following is a specification.

This invention relates to an improvement in stockings wherein separate stalls are provided for the toes of the wearer, and provision also made for the convenient insertion 10 of the toes into the proper stalls.

The ordinary stocking is more or less close fitting and in the provision of stalls 15 for the toes, as heretofore proposed, more or less difficulty has been encountered in properly applying the stocking. The present invention aims to remove this difficulty by materially increasing the space within 20 the stocking at the juncture of the foot proper with the stalls, to permit such freedom of movement of the toes as will allow of their convenient entrance into the proper stall.

25 In the accompanying drawings:—

Figure 1 is a perspective view of the improved stocking.

Fig. 2 is a broken sectional view on the line 2—2, Fig. 1, showing the stocking enlargement at the base of the stall.

The improved stocking 1, which otherwise may be of any desired type or form, is provided in the usual toe portion with a series of stalls 2, of a size and shape to separately 35 receive the toes of the wearer.

The stocking foot, at the junction with the stalls is so formed as to provide increased

material, as compared with the ordinary stocking at this point. This increased material results in a fullness, as 3 directly at 40 the base of the stalls, as clearly shown in the drawings.

In the application of the stocking the ends of the toes at the base of the stalls, are, by reason of the fullness 3, permitted an increased movement laterally and vertically, to 45 permit their convenient insertion into the proper stalls, without disturbing the relation of the other stalls, or so distorting the stocking as to deflect or partly close the 50 stalls.

The improved stocking by enveloping the individual toes prevents direct contact of the toes, and thereby tends to obviate corns and other troubles incident to perspiration and 55 rubbing action. Furthermore, with proper material for the stocking the individual toes are each incased in a protective covering, tending to their more effective protection in cold climates.

60 What is claimed as new is:—

A stocking having a leg portion and a foot portion, the end of the foot portion having individual stalls for the toes, the material of the foot at the base portions of the 65 stalls being of increased length transversely of the foot as compared with the similar length of material beyond such point, whereby to provide a permanent relatively increased space within the stocking at the 70 entrance to the toe stalls.

In testimony whereof I affix my signature.

THOMAS G. CRAIGHEAD.
